CLAIM

The ornamental design for a water bottle stand, as shown and described.

DESCRIPTION

FIG. 1 is an isometric top right view of a water bottle stand in a first environment of use showing our new design.

FIG. 2 is an isometric top right view of a water bottle stand in a second environment of use showing our new design.

FIG. 3 is a right side orthogonal view of the water bottle stand of FIG. 1; the left side orthogonal view of the water bottle stand of FIG. 1 is the mirror image of FIG. 3.

FIG. 4 is a back side orthogonal view of the water bottle stand of FIG. 1.

FIG. 5 is an enlarged view of FIG. 3 taken at “5”.

FIG. 6 is an enlarged view of FIG. 4 taken at “6”.

FIG. 7 is an isometric top right view of the water bottle stand of FIG. 9 folded together and the top element detached.

FIG. 8 is a right side orthogonal view of FIG. 7; the left side orthogonal view of FIG. 7 is the mirror image of FIG. 8.

FIG. 9 is a front side orthogonal view of a water bottle stand showing our new design.

FIG. 10 is a top plan view of the water bottle stand of FIG. 9; and,

FIG. 11 is a sectional view of FIG. 9 taken at “11-11”.
